CLAIM

The ornamental design for a wall shelf, as shown and described.

DESCRIPTION

FIG. 1 is a top perspective view of my new design;
FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the wall shelf form no part of the claimed design.
